UNITED STATES PATENT OFFICE.

ANTON BRUFLAT, OF BARNEVELD, WISCONSIN.

WIRE-SECURING CLIP.

1,214,749.

Specification of Letters Patent. Patented Feb. 6, 1917.

Application filed May 6, 1916. Serial No. 95,872.

To all whom it may concern:

Be it known that I, ANTON BRUFLAT, a citizen of the United States, residing at Barneveld, in the county of Iowa and State 5 of Wisconsin, have invented certain new and useful Improvements in Wire-Securing Clips, of which the following is a specification.

This invention relates to wire securing 10 clips or staples for use in mounting strand wires or a fence webbing in the proper relation, and more particularly to such devices as are adapted for use upon metal fence posts.

15 Metal fence posts are ordinarily made up of sheet metal shaped to the proper form and provided with aligned slotted openings throughout the height thereof to have the single strand of wire or the line wires of 20 a fence web placed adjacent thereto and have a single securing wire looped through the slotted openings from the rear of the post to engage over the single strand or over the line wires of the webbing, but with such 25 a structure as this it is necessary to place the securing wire through the slotted openings and back again, and further it is not possible to remove a single wire without disturbing the securing means for the remaining wires.

With these points in mind, it is an object 30 of my invention to so construct a clip that an anchoring portion may be fitted through the slotted openings of steel or metal posts 35 as now constructed and the clip may then be turned to permit fitting of the wires to be secured between wire engaging fingers which will when bent down around the wire not only secure the wire in the proper 40 mounting on the post but will at the same time hold the clip against turning movement to a relation in which the anchoring portions might become disengaged in the slotted openings.

45 A further object is to so construct the clips that they can be fitted in place and clenched over the line wires of a fence webbing, over a single strand of wire or over a strand of barbed wire to secure the same in 50 the proper mounting upon the post, and can be subsequently opened to release the wire, after which they may be again re-used.

With the above and other objects in view, my invention consists in certain novel features of construction and combinations of 55 parts which will be hereinafter set forth

in connection with the drawings and then more particularly pointed out in the claims.

In the drawings: Figure 1 is a view, in perspective, of a clip constructed after the 60 manner of my invention with the holding fingers thereof closed and showing the relative positioning of the post by dotted lines. Fig. 2 is a view in elevation of a metal fence post with the clip shown in the relation in 65 which it will be fitted into the slotted openings of the post. Fig. 3 is a view similar to Fig. 2 but showing the clip turned to the operative relation.

The clip may be stamped or otherwise 70 shaped to the desired form and as is shown, this clip or staple is made up of a single piece of wire. The central portion of the piece of wire is left straight to form the body 1 of the anchoring portion and the 75 ends are then looped over to one side as shown at 2 and 3 and at the approximate center of the body portion 1 are bent forwardly in the arms 4 and 5 which are curved outwardly and then hooked over to form the 80 securing fingers 6 and 7.

As the device is manufactured, the securing fingers 6 and 7 which are of hooked like form are so disposed that a space is left between their ends, as is shown in Figs. 2 85 and 3, the relations of the parts illustrated in Fig. 1 being that after the securing fingers are clutched or bent down to the securing relation.

The post 9 which is shown here as being 90 of the usual sheet metal construction shaped to the proper form is provided with the slotted openings 10 made of a length slightly greater than one-half the length of the body portion 1, and by fitting the body portions 1 through this slotted opening and then turning the clip to the relation shown in Fig. 3, the body portion will act to anchor the clip against being again pulled forwardly through the slotted openings so 95 long as the clip is maintained in this relation, and then when the securing fingers 6 and 7 are bent down to the relation shown in Fig. 1 where they embrace the wire, the staple will be mounted in a relation to lock 100 the wires and to be also locked against removal from the post.

In the use of the staple or clip, the fence web or strand wires may be clipped adjacent to the post and the clips or staples may 110 be mounted through the slotted openings of the post and brought to the relation shown

in Fig. 3 after which the line wires of the web or the strand wires may be fitted between the holding fingers 6 and 7 and a pair of pliers may be used to pinch these fingers 6 and 7 together so that the extreme ends thereof will overlap and the wire will thus be clenched within the clip to be held against displacement. As the fingers 6 and 7 will be brought down against the wire, 10 the clip will be held against return movement to the relation shown in Fig. 2 where they would be permitted to become displaced through the slotted openings, and the clips will be positively held and will 15 also positively secure the wires against displacement.

If it is desired to release the wires, it is only necessary to pry apart or otherwise separate the fingers 6 and 7 and then the 20 grasp of the clips around the wires against the post is released and not only may the wire be removed from the clip, but also the clip may be turned substantially a quarter revolution where it may be removed through 25 the slotted openings, and if the wire from which the clips are constructed be of sufficient resiliency and elasticity, the clips may be used and reused a number of times.

From the foregoing it will be seen that I 30 have provided a lock wire staple or clip for metal posts which is so constructed that such web or strand wire may be secured about the post, also that although the wires and the clips are positively held against displacement by the closing of the clips upon 35 the wires, these parts may be equally as readily opened without destroying the utility of the clip and both wires and clips will be released, and while I have herein shown 40 and described only one specific form of the device, it will be understood that slight modifications and variations might be resorted to without departing from the spirit and scope of my invention, and hence I do 45 not wish to be limited to the exact disclosure

but only to such points as may be set forth in the claims.

I claim:

1. A wire securing clip for use in conjunction with a metal post having elongated openings therein, comprising a single piece of wire bent and folded upon itself to form an elongated and substantially flat anchoring portion to be received through one of the openings of the post and to be held in place therein as the clip is given a quarter turn, and a portion of the wire shaped to be closed upon the line wire which is to be secured and to thus fasten the line wire in place on the post and at the same time hold the clip against return movement to the relation in which it can be removed from the opening of the post.

2. A wire securing clip for use in conjunction with a metal post having slotted 65 openings therein, comprising a single piece of wire bent up and shaped to form an elongated anchoring portion, the ends of the wire being bent angularly from one side of the anchoring portion and then shaped to 70 form securing fingers originally disposed in a spread relation, and all of said parts being so arranged that the anchoring portion may be inserted through the slotted opening and when the clip has been turned to dis- 75 pose the anchoring portion in a relation to be held against displacement the wire to be secured may be inserted between the fingers and these fingers may be closed down upon the wire to secure the same against displacement and to also hold the clip against turning movement to become dislodged from the anchoring relation within the slotted opening.

In testimony whereof I affix my signature 85 in presence of two witnesses.

ANTON BRUFLAT.
